BENCH

Robert L. Smith and Maxie M. Sullivan,
Lubbock, Tex.

Application July 25, 1950, Serial No. 11,384

Term of patent 14 years
(Cl. D15—11)

To all whom it may concern:

Be it known that we, Robert L. Smith and Maxie M. Sullivan, citizens of the United States of America, residing at Lubbock, in the county of Lubbock and State of Texas, have invented a new, original, and ornamental Design for Bench, of which the following is a specification, reference being had to the accompanying drawing, forming part thereof.

In the drawing:

Figure 1 is a front elevation of a bench, showing our new design;
Figure 2 is an end elevation;
Figure 3 is a rear elevation; and
Figure 4 is a top plan view.

The opposite end is similar to that shown in Figure 2.

We claim:

The ornamental design for a bench, as shown and described.

ROBERT L. SMITH.
MAXIE M. SULLIVAN.
